SADDLE

Arthur D. Hayes, Elyria, Ohio, assignor to The Troxel Manufacturing Company, Elyria, Ohio, a corporation of Ohio

Application June 15, 1936, Serial No. 85,211

2 Claims. (Cl. 208—15)

This invention relates to saddles and more particularly to saddles of the general type employed on cycles.

Some types of saddles heretofore manufactured possessed numerous objectionable features especially from the viewpoint of manufacturing costs, appearance after some use, and the inability of the saddle to stand up after a period of time due particularly to the process of manufacture.

It is therefore one of the objects of the present invention to produce a saddle of the type referred to which will either eliminate the above objections or materially improve these conditions thus resulting in an improved saddle.

A further object of the invention is to produce a saddle which is less expensive to manufacture by reason of the fact that it requires considerably less material in its construction thus eliminating considerable hand labor formerly required.

A still further object of the invention is to provide a new and novel means by which the saddle top is adopted for connection with the reinforcing plate.

With the objects above indicated and other objects hereinafter explained in view, my invention consists of the construction and combination of elements hereinafter described and claimed.

Referring to the drawings,

Figure 1 is a top plan view of a saddle embodying the present invention.

Figure 2 is a longitudinal sectional view taken on line 2—2 in Figure 1.

Figure 3 is a bottom plan view of the saddle shown in Figure 1.

Figure 4 is a fragmentary sectional view taken on line 4—4 in Figure 3 and showing the invention in detail on an enlarged scale.

Figure 5 is a fragmentary sectional view similar to Figure 4 but showing the relationship of elements at one step in the process of assembly.

In the drawings I have shown one type of saddle for the purpose of illustrating the invention, but it should be understood that the invention is as readily adapted for use in connection with other types.

The saddle comprises a sheet metal plate 10 generally triangular in contour and conforming to a desired saddle shape, the plate consisting of a pommel portion 11 and a cantle portion 12 and a depending marginal flange 13 extending entirely around the plate and preferably formed integral therewith. Screwthreaded lugs 14 are connected 55 to the plate and project downwardly from the

under side by means of which the saddle is adapted for connection with any suitable spring suspension means in a well known manner.

The saddle top construction is adapted to be supported by the metal plate 10 and comprises 5 in the present instance, a plurality of layers of fabric material 15 arranged in superimposed relation and adhesively pressed into a unitary structure. This top portion is formed in a complementary shape with respect to the metal plate 10 10 and is then assembled thereon in a well known manner. A padding material 16, preferably finely comminuted sponge rubber, is disposed between the top portion 15 and the metal frame 10 and held in place by means of the connection 15 between the two.

Ordinarily, a similar bottom construction is employed which is preformed and fits upon the under side of the metal plate 10, being secured by means of an adhesive. In the first place it is 20 extremely difficult to get a suitable adhesive which will securely hold the preformed bottom fabric to the metal plate 10 and especially is this true after the saddle has been in actual use for some time and subjected to atmospheric conditions. This is principally due to the particular shape of the under surface of the metal plate 10 25 and when this under portion separates from the metal plate it becomes unsightly and is therefore a detriment to the appearance of the saddle. 30 This under portion further plays no part in the structural features of the saddle and functions solely as a covering for the under side of the plate and its use unnecessarily increases the manufacturing cost of the saddle. For this reason the present invention provides a connection 35 between the top portion 15 and metal plate 10 of the saddle which permits the elimination of this under portion and the necessary operations in its production. 40

I provide a narrow strip of fabric 17, sized or otherwise preferably stiffened, upon the under side of the metal plate 10 which extends coextensively with the flange 13 and is preferably adhesively connected thereto as more clearly shown 45 in Figures 3 and 4. The outer edge portion 18 extends beyond the adjacent edge of the flange 13 and is coextensive with the free edge of the top portion 15 as more clearly shown in Figure 4 to permit stitching of the members together 50 after a binding or finishing strip 19 has been placed around the free edges.

To additionally secure the strip 17 to the metal plate 10 I provide a plurality of tongues 20 arranged in spaced relation around the flange 13 55

as more clearly shown in Figure 3 which are preferably formed by stamping substantially U shaped cuts in the flange 13 and pressing the intermediate portions inwardly to provide the 5 tongues, which normally extend at substantially right angles to the flange 13 more clearly shown in Figure 5. With the tongues thus arranged it is a simple matter to force the strip 17 over the ends thereof and to thus bend the tongues back 10 toward their respective openings with the result that the fabric strip 17 is securely held against accidental displacement.

Of course there are many ways in which these 15 tongues may be formed and pressed into engagement with the fabric strip 17 but I preferably desire to employ the die which presses the preferred parts into a unitary structure and this is readily accomplished by merely having the male die engage the extended tongues in its downward 20 movement to securely press the latter into co-operating engagement with the fabric strip 17.

While I have described the preferred embodiment of the invention it is to be understood that I am not to be limited thereto inasmuch as 25 changes and modifications may be resorted to

without departing from the spirit of the invention as defined in the appended claims.

What is claimed is:

1. A saddle for cycles comprising a metal plate conforming generally to the form of the saddle, 5 a covering on one side of said plate, and a band on the opposite side of said plate and extending around the marginal edge portion of the latter, said plate being provided with a plurality of tongues projecting through said band and adapted 10 to engage the latter to prevent accidental disengagement therebetween.

2. A saddle for cycles comprising a metal plate conforming generally to the form of the saddle and having a depending marginal flange ex- 15 tending therearound, a non-metallic covering on one side of said plate, and a non-metallic band on the opposite side of said plate and extending around the marginal edge portion of the latter, the flange on said plate being provided with a 20 plurality of tongues projecting through said non-metallic band and adapted to engage the latter to prevent accidental disengagement therebetween.

ARTHUR D. HAYES. 25
